ELEVATOR LEVELING DEVICE

Adolph Edward Thurber, Jr., Brooklyn, N. Y.

Application June 19, 1945, Serial No. 600,341

8 Claims. (Cl. 187—32)

1

This invention relates to an automatic leveling device for elevators and more particularly to electric control means for hydraulic elevators.

One of the objects of the invention is to provide a leveling device to bring the car to a stop level with the floor landing with a higher average of speed, and maintain the car level with the landing during loading and unloading.

Another object is to supply electric means including stationary cams in the elevator shaft which control the actuation of switches, and which in turn is controlled by a torque motor, so that the switches can only be operated when arms carried by the elevator are in a position to engage the cams. Thus if the car control lever, which also controls the torque motor, is put in a neutral position between floors, no current can pass through said switches, and consequently valves controlled by said switches will not be actuated to disturb the position of the car between floors.

With the foregoing objects outlined and with other objects in view which will appear as the description proceeds, the invention consists in the novel features hereinafter described in detail, illustrated in the accompanying drawings, and more particularly pointed out in the appended claims.

In the drawings:

Fig. 1 is a diagrammatic view partly in elevation and partly in vertical section of the apparatus with certain parts omitted in the interest of illustration.

Fig. 2 is a side elevation of the switch box and torque motor of the apparatus.

Fig. 3 is a transverse vertical sectional view of the switch box.

Fig. 4 is a vertical sectional view of the switch box, taken at right angles to the section in Fig. 3 and showing the switch in open position.

Fig. 5 is a view like Fig. 4 but showing the switch closed.

Fig. 6 is a similar view with the switch in retracted position.

Referring to the drawings, 10 designates the main cylinder of the elevator, in which the plunger 11 carrying the car 12 operates. 13 designates one of the floors and 14 the usual main valve, connected to pressure supply 15 and to exhaust 16. 17 is an automatic valve of conventional construction, and 18 is the to-and-from pipe connecting it to the top of the cylinder 10.

The auxiliary device for bringing the car back to the floor when it has dropped below includes a pressure pipe 19 tapped from supply 15 and

2

connected to valve casing 20 containing a reciprocating plug, not shown. This supply pressure passes from valve casing 20 through pipe 21, and the automatic valve, to to-and-from pipe 18.

5 The stem of the valve 20 is actuated by a solenoid 22, controlled by means hereinafter described.

A similar mechanism is provided for the exhaust side to bring the car back to the floor when it has ascended above and it comprises an exhaust pipe 23, exhaust valve casing 24, and exhaust pipe 25, leading to to-and-from pipe 18. This valve is also actuated by a solenoid 26 by means hereinafter described.

27 is a filter in supply pipe 19, and 28 is a similar 15 filter in exhaust pipe 25. 29 and 30 are manually adjustable valves for controlling the rate of flow in the respective supply and exhaust pipes 19—21 and 23—25 to determine the speed of returning the car to level position, or to entirely cut off 20 flow through electrically operated valves 20, 24.

The valves 20, 24 are similarly constructed, and each may be of the type shown in U. S. Patent No. 1,633,217.

Fixedly mounted in the elevator shaft at each 25 floor is an abutment means comprising a pair of cams 31 and 32 which are spaced apart and arranged one above the other, and designed to actuate respectively extensible and retractable members or arms 33 and 34 of the solenoid valve control means, when such arms are in projected position.

30 Mounted at the top of the car (Fig. 6) is a switch casing 35 (Figs. 2—6) provided at the interior of one wall with sets of contacts, one set 35 consisting of four contacts 36, 37, 38 and 39, (Fig. 1) and the other set consisting of contacts 40, 41, 42 and 43. The contacts 36 to 39, inclusive, cooperate with a bridge piece 44 carried by a switch arm 45, and the contacts 40 to 43, inclusive, 40 cooperate with a bridge piece 46 carried by a switch arm 47. These arms are of similar construction and are pivotally mounted at their lower ends upon a shaft 48 forming part of a bail, having sides 49 pivotally mounted on a shaft 50, journaled in the casing. Each switch arm is connected by a switch-opening tension spring 51, to a bracket 52 fixed in the casing and each bracket supports a screw 53 to limit the movement of the bridge piece away from the contacts.

50 A rocking lever 54, fixed to a rock shaft 55, is provided with an arcuate notch or slot 56 for the reception of a rod 57 having its ends fixed to the sides of the bail, and it may be seen that if the rocking lever 54 is moved in a clockwise direction, its slot will cause the rod 57 to rise and move the

bail in a clockwise direction about the axis of the shaft 50 to place the switch bridge pieces 44 and 46 in a retired position (Fig. 6).

Each of the arms 45, 47 is provided with a tail 58 cooperating with a roller 59 supported by an upstanding arm 60 of a multi-armed lever. One of these levers (Fig. 3) is keyed to a rocking member or rock shaft 61, journaled in the casing and fixed to the lever 34 which cooperates with the stationary cam 32. The other one of the multi-armed levers is fixed to a rocking member to rock sleeve 62, journaled on the shaft 61 and carrying the lever 33 which cooperates with the cam 31.

Each of the multi-armed levers has an arm 63 cooperating with a compression spring 64 mounted on the floor of the casing and functioning to yieldingly hold the multi-armed lever in a position where its roller 59 is not pressing against the tail 58 of one of the levers 45, 47. Another arm 65 of each multi-armed lever is arranged to abut against an adjustable screw 66 secured to the bottom of the casing. The springs 64 urge the arms 65 toward the adjustable stops 66, and normally hold the arms 33 and 34 projected so they will engage the cams 31 and 32.

Rollers 67 supported by arms 68 depending from and fixed to the shaft 55, abut against the arms 63 of the multi-armed levers for depressing those arms when the arms or levers 33 and 34 are to be moved to a neutral position where they will not contact the cams 31 and 32, as the elevator moves in the hatchway.

An arm 69 is fixed to one end of the shaft 55 and arranged at the exterior of the casing 35, and is connected by a link 70 to the crank 71 of a torque motor 72, mounted on a bracket 73 (Fig. 2) at the exterior of the casing. The arm 69 is also connected to the piston rod 74 of a dashpot 75.

As shown in Fig. 1, the torque motor is controlled by a switch 76 actuated by a lever 77 that moves with the main control handle in the car of the elevator. When the member 77 is in neutral position, the switch 76 is open and the torque motor is de-energized. When, however, the control member 77 moves either to one side or the other, about its axis 78, the switch 76 will close and cause the torque motor to be energized so that it in turn will effect the retraction of the arms 33 and 34 so those arms will not contact with any of the cams 31 and 32 as the elevator travels in the hatchway.

Referring to the wiring diagram shown in Fig. 1, it will be noted that the contacts 37 and 39 lead to the solenoid 26 of the "down" valve 24, and the contacts 36 and 38 lead to the line wires 79 and 80. Consequently, when the bridge piece 44 closes this switch, the solenoid 26 will be energized to open valve 24 to discharge liquid from cylinder 10 and cause the elevator to descend.

The contacts 41 and 43 lead to the solenoid 22 of the "up" valve 20 and the contacts 40 and 42 lead to the line wires. Therefore, when the bridge piece 46 closes this switch, the valve 20 will be opened to admit liquid to cylinder 10. It will thus be appreciated that when the elevator is to be stopped at a floor level, and if the car descends therebelow, the cam 32 will cause the bridge piece 46 to close its switch and operate valve 20 to cause pressure fluid to flow through pipe 18 into the main cylinder 10 until the car is brought to the floor level. On the other hand, if the car at the time it is supposed to stop at a floor level, is slightly above this level, the cam 31

will actuate the bridge 44 so as to energize the solenoid 26 and open the valve 24 to permit pressure fluid to exhaust from the cylinder 10 until the car descends to the desired level.

Whenever the main controller of the car is in a position to cause ascent or descent of the car, it is obvious that the closed switch 76 will cause the torque motor to be energized so that the rocking lever 54 will lift the rod 57 and retire the switch arms to the position shown in Fig. 6, and also cause the multi-armed levers to shift to a position where the arms 33 and 34 will be substantially in vertical alignment and out of position where they would contact with the cams 31 and 32.

From the foregoing, it is believed the construction, operation and advantages of the leveling device may be readily understood and it will be evident to those skilled in the art that changes may be made in the details disclosed without departing from the spirit of the invention, as expressed in the following claims.

What I claim and desire to secure by Letters Patent is:

- 25 1. In a mechanism for controlling the floor leveling of an elevator, a switch arm including a tail, a movable bail pivotally supporting said switch arm, rigid means on said bail, a swingable arm for normally engaging said tail to move the switch arm to a switch closing position, a rockable lever, and means carried by the rockable lever cooperating with said rigid means for shifting said bail to position said tail out of the path of movement of said swingable arm.
- 30 2. In a floor leveling control mechanism for an elevator, a switch arm, swingable means pivotally supporting said switch arm, a swingable arm for normally engaging and moving the switch arm to a switch closing position, a movable lever, a pin carried by said means, and a cam surface carried by said movable lever for shifting said means to a position where the switch arm cannot be engaged by said swingable arm.
- 35 3. In a self-leveling mechanism for an elevator car movable in a hatchway, an electrically operated valve, a switch carried by said car for controlling the supply of current to and the shutting off of current from the valve, a swingable member, a switch arm mounted for pivotal movement on said member, a lever adapted to engage said arm for moving the switch into closed position, a rocking member for actuating the lever, a movable member operatively connected to the rocking member, abutment means mounted in said hatchway adapted to actuate the movable member as the latter moves relatively to the abutment means, and means for moving the movable member into a position where it cannot engage the abutment means and for moving the switch arm into a position where it cannot be actuated by said lever.
- 40 4. In a leveling device for an elevator car movable in a hatchway, an electrically controlled valve, a switch carried by the elevator car and controlling said valve, said switch including a switch arm, swingable means supporting said switch arm, a multi-armed lever arranged to normally engage the switch arm for closing the switch, spring means normally holding the multi-armed lever in one position, a movable member actuated by said multi-armed lever, a substantially stationary cam mounted in the hatchway adapted to be engaged by said movable member when the latter is in a projected position and moves
- 45 5. In a leveling device for an elevator car movable in a hatchway, an electrically controlled valve, a switch carried by the elevator car and controlling said valve, said switch including a switch arm, swingable means supporting said switch arm, a multi-armed lever arranged to normally engage the switch arm for closing the switch, spring means normally holding the multi-armed lever in one position, a movable member actuated by said multi-armed lever, a substantially stationary cam mounted in the hatchway adapted to be engaged by said movable member when the latter is in a projected position and moves
- 50 6. In a leveling device for an elevator car movable in a hatchway, an electrically controlled valve, a switch carried by the elevator car and controlling said valve, said switch including a switch arm, swingable means supporting said switch arm, a multi-armed lever arranged to normally engage the switch arm for closing the switch, spring means normally holding the multi-armed lever in one position, a movable member actuated by said multi-armed lever, a substantially stationary cam mounted in the hatchway adapted to be engaged by said movable member when the latter is in a projected position and moves
- 55 7. In a leveling device for an elevator car movable in a hatchway, an electrically controlled valve, a switch carried by the elevator car and controlling said valve, said switch including a switch arm, swingable means supporting said switch arm, a multi-armed lever arranged to normally engage the switch arm for closing the switch, spring means normally holding the multi-armed lever in one position, a movable member actuated by said multi-armed lever, a substantially stationary cam mounted in the hatchway adapted to be engaged by said movable member when the latter is in a projected position and moves
- 60 8. In a leveling device for an elevator car movable in a hatchway, an electrically controlled valve, a switch carried by the elevator car and controlling said valve, said switch including a switch arm, swingable means supporting said switch arm, a multi-armed lever arranged to normally engage the switch arm for closing the switch, spring means normally holding the multi-armed lever in one position, a movable member actuated by said multi-armed lever, a substantially stationary cam mounted in the hatchway adapted to be engaged by said movable member when the latter is in a projected position and moves
- 65 9. In a leveling device for an elevator car movable in a hatchway, an electrically controlled valve, a switch carried by the elevator car and controlling said valve, said switch including a switch arm, swingable means supporting said switch arm, a multi-armed lever arranged to normally engage the switch arm for closing the switch, spring means normally holding the multi-armed lever in one position, a movable member actuated by said multi-armed lever, a substantially stationary cam mounted in the hatchway adapted to be engaged by said movable member when the latter is in a projected position and moves
- 70 10. In a leveling device for an elevator car movable in a hatchway, an electrically controlled valve, a switch carried by the elevator car and controlling said valve, said switch including a switch arm, swingable means supporting said switch arm, a multi-armed lever arranged to normally engage the switch arm for closing the switch, spring means normally holding the multi-armed lever in one position, a movable member actuated by said multi-armed lever, a substantially stationary cam mounted in the hatchway adapted to be engaged by said movable member when the latter is in a projected position and moves
- 75 11. In a leveling device for an elevator car movable in a hatchway, an electrically controlled valve, a switch carried by the elevator car and controlling said valve, said switch including a switch arm, swingable means supporting said switch arm, a multi-armed lever arranged to normally engage the switch arm for closing the switch, spring means normally holding the multi-armed lever in one position, a movable member actuated by said multi-armed lever, a substantially stationary cam mounted in the hatchway adapted to be engaged by said movable member when the latter is in a projected position and moves

for moving said swingable means to a position where the switch arm cannot be engaged by the multi-armed lever and for moving the multi-armed lever against the action of said spring to shift said movable member to a position where it cannot engage the cam.

5. In a leveling device for an elevator car movable in a hatchway, an electrically controlled valve, a switch carried by the elevator car and controlling said valve, said switch including a switch arm, swingable means supporting said switch arm, a multi-armed lever arranged to engage the switch arm for closing the switch, spring means normally holding the multi-armed lever in one position, a movable member actuated by said lever, a substantially stationary cam mounted in the hatchway arranged to be engaged by said movable member when the latter is in a projected position and moves with the elevator car past the cam, and means for moving the swingable means to a position where the switch arm is out of the path of movement of said multi-armed lever and for moving the multi-armed lever against the action of said spring and shifting said movable member to position where it cannot engage the cam.

6. In a floor leveling control mechanism for an elevator, means mounted for swinging movement, a switch arm mounted for pivotal movement on said swingable means, a movable arm for normally engaging and moving the switch arm to an operable position, a movable lever having a cam shaped slot therein, means carried by the swingable means extending into said slot, and means for moving said lever to shift said swingable means and the switch arm to a position where the switch arm cannot be engaged by said movable arm.

7. In a floor leveling control mechanism for an elevator car, a switch arm, a bail including side members, means supporting said bail for swinging movement, means supporting said switch arm for movement on said bail, a movable arm

mounted to normally engage the switch arm and move the same to an operative position, a lever having a cam shaped slot therein, and a pin carried by the side members of said bail extending into said cam shaped slot whereby the bail is moved to position the switch arm out of the path of the movement of said arm upon movement of said lever.

8. In a floor leveling mechanism for an elevator car which is movable in a hatchway, swingable means, a switch arm mounted for pivoting movement on said swingable means, a movable arm for normally engaging and moving the switch arm to an operative position, a lever, means cooperating with said lever and said swingable means for shifting the switch arm to a position outside the path of said arm, a cam mounted in said hatchway, a movable member operatively connected to said arm and adapted to normally engage said cam, a torque motor, and means between the torque motor and said arm for moving the movable member to a position outside the path of said cam.
